UNITED STATES PATENT OFFICE.

F. R. WALKER, OF TULLY, MISSOURI.

IMPROVEMENT IN STEAM-BOILERS.

Specification forming part of Letters Patent No. 18,875, dated December 15, 1857.

To all whom it may concern:

Be it known that I, F. R. WALKER, of Tully, in the county of Lewis and State of Missouri, have invented certain new and useful Improvements in Steam-Boilers; and I hereby do declare that the following is a full and exact description thereof, reference being had to the accompanying drawings, and to the letters of reference marked thereon.

Figure 1 is a sectional view of a perpendicular boiler, showing the improvements. Fig. 2 is a view of one of the flue-sheets, showing the position of the flues. Fig. 3 is a view of the scraper and a portion of a flue. Fig. 4 is a view of one of the kinds of scrapers used to clean the flues. Fig. 5 is a view of a scraper with a corrugated edge.

To enable others skilled in the art to make and use my invention, I will proceed to describe its construction and operation.

In the construction of my invention Fig. 1 is a sectional view of a perpendicular boiler, showing its improvements and their arrangement.

A is what I shall call an "upper water-chamber," and when in use it is to contain water in it as high as the dotted lines, the remainder of the space to be occupied by the steam. B is what I term a "lower water-chamber." These two water-chambers are connected together and a communication formed between them by the flues marked C C C C. These flues are made in the ordinary manner and are fastened into the flue-sheets D and E. These flue-sheets form the bottom of the upper water-chamber A and the other forms the top of the lower water-chamber B. The lower water-chamber is suspended from the upper water-chamber, and is sustained by the flues C C C C for the purpose of allowing the said flues to expand and contract without starting their joints at the point where they join the flue-sheets D and E, which it otherwise would do if this provision was not made. (This is a point which should be particularly noticed, as it will be readily seen that by this arrangement a defect which has always been of considerable annoyance to engineers when using small-flued boilers is effectually overcome; therefore has a tendency to make a set of flues last for a longer period.) The reason why small flues get loose at the joint and produce a leakage

between said flues and flue-sheet is because they expand and contract quicker than any other part of the boiler. Therefore the flue-sheet must be sprung out or in, as the case may be, or the joint must become loose, causing a leak around the said joints.

F are partitions between the flues for the purpose of turning the fire in proper directions to produce an equal and perfect circulation of the heat among the said flues.

G is the chimney or exit for the smoke.

H is the passage for the fire from the furnace to the flues.

I is the furnace or fire-chamber.

J is the mud-valve.

K represents pipes connecting with the pumps to supply the boiler with water.

L is the man-hole or entrance to the inside of the lower water-chamber for the purpose of allowing it to be cleaned out when desirable.

M is the water-gage cock for the purpose of knowing what the height of the water is in the upper water-chamber.

N is the dry-pipe to allow the steam to pass from the boiler to the cylinders of the engine.

O is the safety-valve.

P P P P P are screw-plugs. These plugs are to be removed when it is found necessary to clean the scale from the inside of the flues C C C C. The holes that receive these plugs are placed directly over said flues. This allows the scrapers to be introduced to clean them from scale and other matter. There is the same number of these screw-plugs as of the flues.

Q is a man-hole or entrance to the upper water-chamber for the purpose of allowing the said chamber to be cleaned.

R R are lugs to support the boiler. These lugs rest upon the case S S. This case forms the outside of the boiler and consists of an outside and inside cylinder made of iron or other material. The inside cylinder is smaller than the outside one for the purpose of leaving a space between them. This space is to be filled with ashes or any other non-conducting material for the purpose of excluding the cold and keeping in the heat, thereby causing a very great saving of heat and fuel. This space is marked T. This kind of casing can be applied to many kinds of boilers with great advantage. It will readily be seen that this kind of a boiler will be very effective and at

the same time be cheap; also, that the fire is applied to almost every part of it at once, which will be found to be of great advantage in saving fuel. It also will be light and can be used as a portable boiler, as it forms its own furnace and chimney, as they form part of it. It can be easily and effectually cleaned, and is, in my opinion, easier kept in repair than any other known kind of boiler.

Fig. 2 is a top view of one of the flue-sheets, showing the position of the flues.

Fig. 3 is a view of one of the scrapers to be used in cleaning the flues; also, a portion of a flue showing the mode of its operation.

Fig. 4 is a view of one of the scrapers. It consists of a circular piece of iron fastened to a long rod or handle.

Fig. 5 is a view of a scraper with its edge corrugated. This scraper will be the first to be run through the flues. The reason why this is used first is because it will furrow or roughen up the scale, so that the circular scraper, which is to be used next, will take off the scale with more ease. Therefore by this means the flues will be thoroughly cleaned.

What I claim is—

The arrangement of the vertical deflecting-plates F in relation to the water-tubes C, the water-spaces B and A, and the furnace and uptake, as herein set forth.

F. R. WALKER. [L. S.]
